UNITED STATES PATENT OFFICE.

HERMANN FINGERHUT, OF BRESLAU, GERMANY.

FLY-CATCHER.

1,029,001.

Specification of Letters Patent. Patented June 11, 1912.

Application filed October 23, 1911. Serial No. 656,136.

To all whom it may concern:

Be it known that I, HERMANN FINGERHUT, a subject of the German Emperor, and residing at Breslau, Germany, have invented certain new and useful Improvements in Fly-Catchers, of which the following is a specification.

The present invention has reference to improvements in fly catchers, and relates more specifically to fly catching devices of the extensible kind, which for shipping and storing purposes are collapsed and for use must be pulled out to their full extent, when the operative surface presented is relatively large; and the particular object of the invention is to provide means whereby the device in collapsed state, when it lies flat and takes up very little room, is so securely sealed that there is no danger of the adhesive mass drying out or exuding, which two causes, as is well known, very soon render most of the now marketed fly catchers useless, or at least greatly reduce their adhesive properties.

In order to make this invention more readily understood, I will now describe it in detail with reference to the accompanying drawing, in which—

Figure 1 represents a perspective view of the device ready for use, on a reduced scale; Fig. 2 shows a plan view of the collapsed and folded-up device; Fig. 3 shows a longitudinal section through Fig. 2; Fig. 4 represents the manner of opening the device.

The device essentially consists of a hollow body *a* of suitable material, preferably paper impervious to liquids and air, which in the drawing, by way of example is given the form of an obelisk, but which may also be in the shape of a bag or sack, a pyramid, or the like. This obelisk with its lower edges is suitably secured to the base plate or support *b*, for instance by being glued thereto, and can readily be folded flat onto the base plate, which latter is preferably hollowed-out or dished in its middle part so that the hollow member, when collapsed, snugly fits into the hollow. To the upper end of the member *a* is secured the handle *c*, preferably in the shape of a string or wire loop, which facilitates handling the device in opening it, and also serves to suspend it.

After the adhesive mixture has been ap-

plied to the outer faces of the hollow member, the latter is collapsed on the base plate 55 and this plate is then folded back upon itself on a center line parallel to two side edges, the loop end *c* partly hanging out, as shown in Fig. 2. The base plate may be made in one and the two halves bent on a 60 weakened line, or it may be composed of two members connected along the bending line in suitable manner, for instance by a strip of gummed paper or fabric. The superposed edges of the plate halves are then 65 sealed by being glued together directly or by means of strips of gummed paper or the like. In order to make this closure still more perfect, the respective plate halves may be so grooved or corrugated, as at *e*, 70 that the convex or ridged part of the one half takes into the corresponding concave or furrowed part of the other half. Adhesive strips *d* then airtightly secure the two support halves in the closed position. 75

In the base plate there is provided an air hole *f*, through which the air, obviously, has access to the interior of the hollow member, but not to the adhesive outer surface thereof, so that drying-out of the sticky medium is 80 effectively prevented as long as the device is collapsed and closed.

For opening and setting up the fly catcher, the protruding end of the handle *c* is gripped and guided along between the 85 pasted-together edges of the base plate, as shown in Fig. 4, whereby the seal between the two halves is broken. The support plate is then unfolded and the adhesive member *a* is set-up by pulling on the handle, and at the 90 same time inflating it by blowing into the aperture *f*.

What I claim is:—

1. In a fly catcher, in combination, a foldable dished base plate having an air vent, a 95 collapsible member airtightly secured thereto so as to inclose said air vent, adhesive substance on the outer surface of said collapsible member, a flexible handle at its free end, said adhesive member adapted to snugly fit 100 the dished portions of said base plate halves in collapsed state, and means for sealing the superposed edges of the folded base plate, substantially as set forth.

2. In a fly catcher, in combination, a foldable base plate comprising two hinged-to-

gether members with interfitting corruga-
tions along the edges, an adhesive member
adapted to be inclosed in collapsed state by
said hinged members, a seal between the
5 folded-together base plate members, and
means for breaking said seal, substantially
as set forth.

In testimony whereof I affix my signature
in presence of two witnesses.

HERMANN FINGERHUT.
